UNITED STATES PATENT OFFICE

114,948

DESIGN FOR A HAMPER OR SIMILAR ARTICLE

Harold Gleitsman, New York, N. Y.

Application July 11, 1938, Serial No. 78,398

Term of patent 14 years

To all whom it may concern:

Be it known that I, Harold Gleitsman, a citizen of the United States, residing in New York, in the county of New York and State of New York, have invented a new, original, and ornamental Design for a Hamper or Similar Article, of which the following is a specification, reference being had to the accompanying drawing, forming part thereof.

The figure is a perspective view of a hamper or similar article embodying my new design. The corner which is not shown in full in the figure is identical with the corner which is completely shown. The elements of the corner portions simulate tiling. The dominant features of the design reside in the parts shown in solid lines.

I claim:

The ornamental design for a hamper or similar article, as shown and described.

HAROLD GLEITSMAN.
